UNITED STATES PATENT OFFICE.

GEORGE R. DELAMATER, OF LAKEWOOD, OHIO.

FLOAT AND SINK TESTING APPARATUS.

Application filed April 26, 1924. Serial No. 709,286.

To all whom it may concern:

Be it known that I, GEORGE R. DELAMATER, a citizen of the United States, residing in the city of Lakewood, county of Cuyahoga, 5 and State of Ohio, have invented certain Improvements in Float and Sink Testing Apparatus, of which the following is a specification.

My invention is an improved apparatus 10 for separating and segregating constituents of different specific gravities comprised in materials to be tested. It is particularly applicable for use in separating and segregating slate and impurities from coal to determine the relative proportions of the carbonaceous and deleterious constituents, and 15 for testing the efficiency of separation as it is performed in various washing devices.

My invention contemplates the separation 20 of the several constituents by means of a solution of such specific gravity as to cause the heavier constituents to sink and the lighter constituents to float and it is the object of my invention to provide means for segregating and handling the constituents so separated in an efficient, expeditious and economical manner.

My invention relates particularly to the means for supporting and operating the sink 30 collector, the float collector and the transfer device by which are effected the segregation, collection and removal from the fluid of constituents separated thereby. For this purpose, I preferably employ a vertically 35 reciprocable bar or shaft having depending from the top thereof a tubular hanger which may be telescoped on and guided by a post or column within the fluid container. The hanger has fixed thereto a bracket provided 40 with arms of suitable elasticity for detachably holding a sink collector and a float collector. A transfer device, revolvably connected with the reciprocable shaft and hanger, is movable along its axis of rotation by 45 means of a cam operable by a journaled shaft providing a lever for rotating the transfer device so as to bring it into registration with the respective collectors.

The vertically reciprocable shaft may be 50 conveniently operated through a geared connection with a revolvable shaft provided with a crank handle, and the reciprocable shaft and parts connected therewith may be held in desired position by suitable latching 55 mechanism.

The characteristic features and advan-

tages of my improvements will more fully appear from the following description and the accompanying drawings in illustration of an embodiment of my invention. 60

In the drawings, Fig. 1 is a top plan view of apparatus embodying my invention; Fig. 2 is a vertical sectional view thereof on the line 2—2 of Fig. 1; Fig. 3 is a transverse sectional view of the apparatus, with a cover 65 added thereto; Fig. 4 is a transverse sectional view of the operating mechanism on the line 4—4 of Fig. 1; Fig. 5 is a partial transverse sectional view taken on the line 5—5 of Fig. 1; Fig. 6 is a fragmentary sectional 70 view of the upper portion of the operating mechanism looking from the rear of the apparatus; and Fig. 7 is a fragmentary transverse sectional view of the construction shown in Fig. 6. 75

As illustrated in the drawings, fluid container or tank 1 is supported upon legs 2 and is provided with the bottom 3 containing an aperture 4. A bracket 5 is fixed to the bottom 3 and has a hub 6 projecting through the aperture 4 into the tank. A tubular post or column 7, tightly sleeved on the boss 6, projects above the fluid level of the tank. 80

A shaft 8, provided with a crank-handle 85 9, is journalled in the bearing 10 and in the bearing 11 depending from the bracket 5. The shaft 8 has fixed thereon a gear wheel 12 which meshes with the rack 13 of a bar or shaft 14 splined in the bracket 5 and hub 90 6 and reciprocable through the shaft 8 by the rotation of the handle 9. The top of the shaft 14 has pinned thereto a flanged collar 15 from which depends a tubular hanger 16 telescoping over and guided by 95 the tube 7.

A sleeve or collar 17 is telescoped on the top of the hanger 16, and has journalled therein a shaft 18 provided with an eccentric cam 19 contacting with the top of the 100 shaft 14. The shaft 18 is revolvable about its axis by means of a handle 20 to rock the cam 19 and move the sleeve 17 vertically relatively to the tube 16, the shaft 18 also providing a lever for rotating the collar 17 105 on the hanger 16. The top of the tube 16 contains notches 16' in which the shaft 18 is seated when the collar 17 is in its lowermost position, whereby the positioning of the collar 17 relatively to the tube 16 may be accurately and easily determined. 110

The collar 17 has clamped thereto a

bracket 21 which has set therein a stud or screw 22' which passes through the collar 17 into an arcuate slot 22 in the tube 16 to limit the rotation of the bracket 21 and 5 sleeve 17, while permitting vertical movement thereof by the cam 19.

The bracket 21 is provided with the curved spring-arms 24 which embrace the periphery of the cylindrical receptacle or 10 transfer device 25 provided with the annular ribs 26 which prevent vertical movement of the receptacle relatively to the bracket arms.

A bracket 27 is clamped upon the tube 16 15 below the plane of the bracket 21, and is provided with two sets of spring arms 28 which embrace the peripheries of the sieve-bottomed pans or collectors 29 between the annular ribs 29' thereon.

20 A shaft 30 is journaled in the bottom of the wall of the tank 1, parallel with the shaft 8, and has fixed thereto an arm 31 connected by a link 32 with a latching slide 33 movable in a way 34 into and out of alignment with the rod 14. The shaft 30 has the end thereof bent to form a handle 35 to provide means for rotating the shaft and operating the slide 34.

In the operation of my apparatus, the 30 tank 1 is partly filled with a suitable solution, such as calcium or zinc chloride solution, of such specific gravity as to float a constituent of the material to be tested and permit the other constituent to sink.

35 The shaft 8 is operated by the handle 9 and acts through the pinion 12 and rack 13 to lower the rod 14 and the parts connected therewith so that the pans 29 are submerged and the receptacle 25 is immersed in the 40 liquid in the container. By rotating the shaft 18 about its axis so as to rock the cam 19, the sleeve 17 and bracket 21 may be moved vertically to disengage the receptacle 25 from the collector pans, and such receptacle may then be rotated about the axis 45 of the ring 17 into registration with the pan which it is desired to use as the sink collector. The shaft 18 is then operated to lower the receptacle within the rim of the 50 sink collector and the material to be tested placed in the receptacle. The heavier constituents, or "sink" of the material being tested will drop into the sink pan 29, while the light constituents, or "float" will float 55 in the open-ended receptacle 25. When complete separation of the constituents has been effected, the handle 20, shaft 18 and cam 19 are rocked to disengage the receptacle 25 from the sink collector, and, by using the 60 shaft 18 as a lever, the receptacle 25 is slowly rotated until it is in registration with the "float" collector which may be the other pan 29. The rocking of the cam 19 engages the receptacle and float pan together. The 65 handle 9 is then rotated to elevate the shaft

14, which lifts the collector pans 29 and receptacle 25 above the surface of the fluid in the tank so that the constituents may be readily removed from the pans for testing. It will be observed that the receptacle 25 70 may be moved to engage or disengage the collector pans in all positions thereof.

Having described my invention, I claim:

1. A float and sink testing apparatus comprising a float collector, a sink collector, and 75 a transfer device, one of said members being revolvable about an axis to effect registration of said device with the respective collectors, and a fluid container for immersing said collectors.

80 2. A float and sink testing apparatus comprising a float collector, a sink collector, and a transfer device, one of said members being vertically movable and rotatable about an axis to effect registration of said device with 85 the respective collectors, and a fluid container for immersing said collectors.

3. A float and sink testing apparatus comprising float and sink collectors, a transfer device, cam mechanism for moving one of 90 said members vertically to effect engagement and disengagement of said device and the respective collectors, and a fluid container for immersing said collectors.

95 4. A float and sink testing apparatus comprising a fluid container, constituent segregating mechanisms comprising sink and float collectors, constituting one of said mechanisms and a transfer device, constituting the other of said mechanisms, means for 100 vertically moving one of said mechanisms, and means for vertically and laterally moving the other of said mechanisms relatively to the first named mechanism in any position thereof.

105 5. A float and sink testing apparatus comprising a fluid container, a vertically movable support, a second support movable vertically and horizontally relatively to said support first named, float and sink collectors 110 connected with one of said supports, and a transfer device connected with the other of said supports.

115 6. A float and sink testing apparatus comprising a fluid container, a vertically movable shaft, a hanger depending from said shaft, sink and float collectors connected with said hanger, and a transfer device supported by said shaft and movable vertically and laterally relatively thereto.

120 7. A float and sink testing apparatus comprising a vertically movable member, float and sink collectors supported by said member, and a transfer device supported by said member and movable vertically and laterally relatively thereto and to said collectors.

125 8. A float and sink testing apparatus comprising a plurality of supports one of which is rotatable relatively to the other, float and sink collectors carried by one of said

supports, a transfer device carried by the other of said supports, and a fluid container for immersing said collectors.

9. A float and sink testing apparatus comprising a sink collector, a float collector, a transfer device, and means for effecting relative movement of said device and collectors and comprising a revoluble support, a shaft journalled in said support and forming a lever for effecting rotation thereof, a cam on said shaft and revoluble thereby, and a bearing engaged by said cam to move said support along its axis of rotation.

10. A float and sink testing apparatus comprising a fluid container having a post therein, a shaft reciprocable relatively to said post, a hanger depending from said shaft and telescoped on said post, a ring sleeved on said hanger, cam mechanism for effecting relative movement of said ring and hanger, means comprising a pin and slot limiting the relative movements of said sleeve and hanger, sink and float collectors connected with said hanger, and a transfer device connected with said ring.

11. A float and sink testing apparatus comprising a fluid container, a supporting member reciprocable relatively to said container, a shaft journalled relatively to said container, gear mechanism connecting said shaft and member, and sink and float collectors supported by said member. 30

12. A float and sink testing apparatus comprising a fluid container, a plurality of constituent collectors, a constituent transfer device, means for effecting simultaneous vertical movement of said collectors relatively to said container, and means for effecting vertical movement of said transfer device 35 relatively to said collectors. 40

13. A float and sink testing apparatus comprising a fluid container, a supporting member disposed in said container, brackets secured to said member and having elastic arms, and collectors provided with radial 45 bearing surfaces engaging said elastic arms.

In testimony whereof I have hereunto set my hand this 22nd day of April, 1924.

GEORGE R. DELAMATER.
